(57) CLAIM

The ornamental design for a bag, as shown and described.

DESCRIPTION

FIG. 1 is a perspective view of a bag showing my new design, shown in a configuration with the handles attached to each other;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a perspective view thereof, shown with the handles in a configuration with the handles detached from each other. The broken lines depict portions of the bag that form no part of the claimed design.

1 Claim, 8 Drawing Sheets
